CLAIM

The ornamental design for a board game, as shown and described.

DESCRIPTION

FIG. 1 is a first perspective view of a board game showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the board game thereof; and,

FIG. 10 is a perspective view of another state of the board game thereof.

The broken lines shown in the drawings depict portions of the board game that form no part of the claimed design.

1 Claim, 10 Drawing Sheets
